(Cl. D29—3)

To all whom it may concern:

Be it known that we, Milton P. Roumm, Julius W. Gehring, and John G. Chapman, all citizens of the United States, residing at Seattle, in the county of King and State of Washington, have invented a new, original, and ornamental Design for a Pin, of which the following is a specification; reference being had to the accompanying drawings, forming a part thereof.

Figure 1 is an isometric front face view of a pin, showing our new design;

Figure 2 is an isometric rear face view thereof.

We claim:

The ornamental design for a pin, as shown.

MILTON P. ROUmm.
JULIUS W. GEHRING.
JOHN G. CHAPMAN.
